UNITED STATES PATENT OFFICE.

WILLIAM S. TOMKINS, OF BOONTON, NEW JERSEY.

HAND COAL-CONVEYER.

SPECIFICATION forming part of Letters Patent No. 319,865, dated June 9, 1885.

Application filed May 4, 1885. (No model.)

To all whom it may concern:

Be it known that I, WILLIAM S. TOMKINS, a citizen of the United States, residing in Boonton, Morris county, New Jersey, have invented certain new and useful Improvements in Hand Coal-Conveyers, fully described and represented in the following specification and the accompanying drawings, forming a part of the same.

10 This invention consists in the combination, with a hand-crank and gearing applied to a sprocket-wheel shaft, of a chain or chains and buckets traversed over the said sprocket-wheel, a frame to support said wheel, and an 15 idle pulley or pulleys at the opposite end of the frame to guide and return the chain to the sprocket-wheel.

It also consists in the combination, with the frame or legs adapted to rest within a coal-car, of a seat adapted to support an operator adjacent to the hand-cranks.

The invention may be used for shifting coal by hand-power from either a boat or from an opening in the bottom of the car.

25 The latter construction is shown in Figures 1 and 2, Fig. 1 representing one end of a coal-car in plan, and Fig. 2 representing the same in elevation, with the nearer side of the car removed to exhibit the operator and machine. 30 Fig. 3 represents a plan of the conveyer applied to a boat and coal-bin. Fig. 4 represents the same parts in elevation, the boat being shown in section at the nearer side of the conveyer. Fig. 5 is a section of the conveyer 35 on line $x-x$ in Fig. 3. Fig. 6 is a diagram of the hand-gearing.

The conveyer is partly adapted for use in the long cars which are frequently employed to transport a large quantity of coal, and from 40 which the coal is discharged through an opening or trap, T, in the center of the bottom. In such cars a sloping bottom has sometimes been used to make the coal flow readily toward such opening; but as the capacity of the 45 car is greatly diminished by such construction a flat bottom is preferable, such as is shown in Fig. 2 at E. With such a bottom, however, and with cars of twenty-five to thirty-five feet in length, it has been necessary to have a large 50 proportion of the coal shoveled from the end of the car to the opening in the middle.

My conveyer is intended to furnish a light portable machine, which may rest directly

upon the coal and operate to shift from the ends toward the middle of the car that portion of the coal which will not flow out of the opening voluntarily. This operation is effected by the movement of the buckets traveling along the under side of the frame and scraping or pushing the coal before them as the operator 55 sits upon the frame and rotates the gearing by hand-cranks attached thereto. This construction is shown in Figs. 1 and 2, where A is a frame formed of two planks connected by cross-ties B. C are legs secured to the frame 60 to rest upon the coal D in the bottom of the car E.

a is the conveyer-chain; b, the buckets thereon; c, the sprocket-wheel, and d the sprocket-wheel shaft.

e is the idle-pulley at the opposite end of the frame, and f its shaft fitted to bearings g upon the frame A.

F is a crank-shaft mounted in bearings upon the frame A adjacent to the shaft d, and provided with cranks h and gear H, which meshes with a gear, G, upon the sprocket-shaft d.

I is a seat secured upon the frame A near the shaft F, upon which the operator J may sit when turning the cranks h.

The entire structure is made very light and portable, and the seat is preferably set back from the end of the frame, as shown in the drawings, so that the chain and buckets may be set close to the end of the car. The legs C 85 are preferably constructed with flat feet C' at the bottom, and these feet are proportioned so as to support the weight of the machine as it rests upon the coal in the car, and sustain the frame at such a distance from the surface of the coal that the scrapers or buckets will operate suitably in propelling the same toward the trap T. The operator's feet may rest upon the front feet C' of the frame, as shown in Fig. 2, the frame and operator settling down 95 together as the coal is scraped from under the machine and the support for the latter gradually diminished. The conveyer may be made of sufficient length to extend entirely over or past the trap T, as the buckets become inoperative as soon as they have discharged their load into the trap, and the extra length thus produces no difference in the operation of the machine, while it adapts it to cars of the greatest maximum length. It may therefore 100 be made of such length that it can be used at

the same coal-yard for shifting the coal either from a car or boat; but when it is used exclusively for the latter purpose a slight change in the arrangement of the crank-shaft may be made, if desired, as it is not requisite that the operator should sit over the frame. In such case two chains may be used instead of one, and larger buckets be employed, as shown in Figs. 3 to 5, inclusive, in which case the buckets would require to be supplied each with one scoopful of coal by an operator placed in the boat adjacent to the frame. The boat is shown at L in Figs. 3 and 4, the lower legs of the frame having their feet supported upon the coal, (indicated at D'), and a screen, S, being arranged beneath the upper end of the frame to receive the coal as it falls from the buckets.

R is a coal-bin situated upon the wharf W, and the frame and screen are sustained upon the coal-bin, as shown in Fig. 4, so that the dust and dirt which pass through the screen may fall or be conducted outside of the bin, as by a chute, so that the coal delivered into the bin will be entirely clean and ready for immediate use. The buckets applied to the double chains are provided with wheels n, and the frame is provided with upper and lower bars, o and p, upon which the wheels may run as the buckets travel up and down upon the frame. The crank-shaft is shown arranged across the frame between the chains in such position that the operator may stand upon a platform, P, outside of the bin, to turn the crank at either side of the frame, as may be most convenient, and fly-wheels K are shown affixed to the cranks to assist in maintaining a uniform motion. The buckets in this device are intended to hold only a scoopful of coal, and to move at such a rate that the operator in the boat may fill them, one at a time, as they pass, and the entire load upon the chain is thus so light that it may be easily elevated by the hand-gearing shown. My invention is therefore adapted for use in many places where steam or horse power is not available, or where the conveyer is seldom required for use, the cheapness of the construction and its lightness and portability rendering it very convenient for application to either the car or boat, as may be desired.

The construction shown in Figs. 1 and 2 is fully adapted for use with the boat by furnishing the buckets with rollers and a track upon which they can travel, as the small buckets employed may be traversed with perfect facility by means of a single chain, and the lower end of the frame may be readily provided with an adjustable leg to adapt it for use in the two different positions required. The hand-gearing shown in Figs. 1 and 2 is equally adapted for use when the conveyer is applied to a boat, the alternative construction in Fig. 4 being shown simply as a modification, and the fly-wheels being equally adapted for use with the conveyer when applied to a car.

As the seat is arranged above the buckets, it is obvious that the precise construction shown in Fig. 2 may be supported by the coal-bin and the operator sit upon the seat to 70 actuate the cranks, the same as when the device is applied to a car.

As the object of the hand-gearing is to increase the power of the operator, although it diminishes the speed of the buckets, it is obvious that the main shaft and crank-shaft may be supplied with chain-wheels and connected with a chain belt, such as is now often used in transmitting motion. To illustrate this construction, the diagram in Fig. 6 shows the end 80 of the frame and the seat with such an alternative gearing, the chain-wheels being proportioned to produce the desired relative speed.

I am aware that it is not new to propel buckets, scrapers, or carriers of any kind by 85 means of a chain and sprocket wheels; and I am also aware that a frame carrying such mechanism is often hinged at one end, where it is connected with a rotating driving-shaft, so as to be movable at the other end, and I 90 do not therefore claim such a construction. But I am not aware that any conveyer-frame has ever been made as an entirely independent structure disconnected from other mechanism and furnished with its own gearing and 95 adapted for operation by hand-power; and my invention therefore furnishes a device capable of use in different situations and in a variety of ways, and therefore possesses functions not heretofore performed by other 100 devices.

Having thus distinguished my invention from others, I claim my particular construction in the following manner:

1. The conveyer consisting of the side 105 frames, A, having the idle-pulley at one end and the sprocket-wheel at the other, the chain or chains carrying the buckets, the gearing to rotate the sprocket-wheel, and the crank-shaft and hand-cranks to operate the gearing and 110 move the chain, substantially as herein set forth.

2. The combination, with the conveyer constructed as herein shown and described, of the screen arranged to receive the coal from 115 the conveyer and to deliver the dirt outside of the bin and the coal into the bin, as and for the purpose set forth.

3. The combination, with the frame having the sprocket-wheels and chains provided with 120 buckets and provided with the gearing and hand-cranks to operate the same, as described, of the seat arranged upon the frame for the operator, adjacent to the hand-cranks, as and for the purpose set forth.

In testimony whereof I have hereunto set my hand in the presence of two subscribing witnesses.

WILLIAM S. TOMKINS.
